(57) **CLAIM**

The ornamental design for the lumbar belt, as shown and described.

DESCRIPTION

FIG. 1 is a rear perspective view of a lumbar belt showing my new design;

FIG. 2 is a rear enlarged fragmentary elevation view thereof; FIG. 3 is another rear enlarged fragmentary elevation view thereof;

FIG. 4 is a front enlarged fragmentary elevation view thereof; FIG. 5 is another front enlarged fragmentary elevation view thereof;

FIG. 6 is a second perspective view thereof, shown in use; and,

FIG. 7 is a third perspective view thereof, shown in use. The broken lines shown are for illustrative purposes only and form no part of the claimed design.
